UNITED STATES PATENT OFFICE.

LAMBERT SCHMIDT, OF BROOKLYN, NEW YORK, ASSIGNOR TO RADIOTIVE CORPORATION, OF BROOKLYN, NEW YORK.

TELEPHONE APPARATUS.

Application filed January 31, 1923. Serial No. 615,981.

To all whom it may concern:

Be it known that I, LAMBERT SCHMIDT, a citizen of the United States, and a resident of Brooklyn, county of Kings, and State of New York, have invented certain new and useful Improvements in Telephone Apparatus, of which the following is a specification.

This invention relates to telephone apparatus and more particularly to a loud speaking receiver especially designed for use in connection with apparatus employed for the purpose of establishing wireless telephonic communication.

In Patent No. 1,452,850, issued April 24, 1923, I have illustrated and described a magnetic structure of this general character. While the device disclosed by said patent is very sensitive to variations in polarity of the alternating currents passing through the translating coil of the telephone magnet, it has been found that in certain respects better results may be obtained by means of the improved device which I shall presently describe, particularly as regards clearness of the sound tones which are produced by vibrations of a sound diaphragm which is connected with the magnet armature.

In my prior construction, as in numerous other types of magnet telephones heretofore employed, the fulcrum for the vibratory armature is located at one side of or out of line with the axis of the armature. It is evident, therefore, that the extent of vibratory movement of the ends of the armature between the opposed magnet poles will be unequal. Accordingly, it is my present purpose, to devise a magnetic structure for such telephone apparatus wherein the fulcrum of the armature will be located exactly in the line of its axis, and at a point which is midway between the opposite ends of the armature disposed between the spaced shoes or branches of the opposed magnet poles. By means of such construction, I have simplified the magnetic structure to a marked extent, appreciably reducing its manufacturing cost and at the same time have succeeded in obtaining noticeably improved results in the loudness and clearness of the tone, in comparison with the results which it is possible to produce by means of such devices heretofore known to the art.

In a more specific aspect, my invention comprehends the provision of an armature

of tubular form and a vibratory support for said armature coaxially related therewith and having a part fixed in one end of the tubular armature whereby said magnet and its support are connected as a unit for arrangement through the bore of the translating coil spool. The support is formed with a reduced resiliently yielding fulcrum portion enclosed by the tubular armature and located centrally between its ends and exactly in the line of the armature axis. Thus, upon change in direction of the alternating currents passing through the coil and variations in the magnetic flux, the tubular armature will vibrate in the core of the spool, and owing to the fact that the fulcrumed point is exactly centered within this tubular armature, the extent of vibratory movement of the armature at its ends between the pole shoes will be exactly equal.

With the above and other objects in view, the invention consists in the improved magnetic structure for telephone apparatus and in the form, construction and relative arrangement of its several parts as will be herein-after more fully described, illustrated in the accompanying drawing and subsequently incorporated in the subjoined claims.

In the drawing wherein I have illustrated one desirable and practical embodiment of the invention and in which similar reference characters designate corresponding parts throughout the several views:

Figure 1 is a rear elevation, the casing being removed to illustrate one embodiment of the magnetic structure;

Figure 2 is a section taken on the line 2—2 of Figure 1;

Figure 3 is a view looking in a direction at right angles to Figure 1;

Figure 4 is an enlarged detail section taken on the line 4—4 of Figure 3;

Figure 5 is an enlarged perspective view of the armature and its vibratory support, the armature being shown in section; and

Figures 6 and 7 are detail perspective views showing several modified forms of the armature support.

As in the patent above referred to, in the embodiment of my present invention, which I have selected for purposes of illustration, there is provided a permanent magnet 5 of conventional U-shaped form. To the inner opposed faces of the parallel legs of this permanent magnet the pole pieces 6 and 7

respectively, are suitably secured, as by means of the screws 8. These pole pieces at their relatively opposite ends are formed with flanges 9 and 10 respectively, projecting inwardly from the attaching arms of the pole pieces. Each flange is provided in its ends with the angularly disposed shoes 11 and 12 respectively, the shoes of each pole piece projecting towards the shoes on the other pole piece and the opposed shoes being positioned in the same plane.

The pole shoes 11 and 12 embrace the cylindrical spool 13 which is of a suitable non-magnetic material and upon which the translating wire coil 14 is wound. The spool 13 has the usual cylindrical bore 15 open at its opposite ends. One edge of the permanent magnet 5 is engaged against the inner face of a front plate 16 also of a suitable non-magnetic material and to this plate the angular portion 9 of the pole piece 6 may be riveted or otherwise securely fixed.

The mounting and arrangement of the permanent magnet, the pole shoes and the translating coil constitute no part of my present improvements and correspond to the arrangement disclosed in said issued patent. The armature and its support which constitute the novel subject matter of the present improvements, are more particularly illustrated in a preferred embodiment thereof in Figures 4 and 5 of the drawing to which reference may now be had. The armature support 17 in a construction which I have found in practice to give the best results, is of phosphor-bronze and is preferably of general cylindrical form. In other words, this support consists merely of a cylindrical rod. The diameter of this rod is determined by the diameter of the tubular armature 18. This armature is of soft iron and the bore 19 thereof is reduced in diameter at one of its ends, as shown at 20. The armature supporting rod 17 is of somewhat greater length than the length of the armature 18 and has a relatively long portion 21 of uniform diameter, a short end portion 22, and an intermediate connecting portion 23. The opposite sides of the rod at the latter portion thereof are cut away or concave, as indicated at 24, thereby providing midway between the portions 21 and 22, a relatively thin section constituting the fulcrum 25 for the armature. From this fulcrum point the portion 23 of the rod gradually increases in thickness to the portions 21 and 22 thereof.

The end portion 22 of the supporting rod 17 is of such diameter that it has a tight frictional fit in the reduced end 20 of the armature bore, as clearly shown in Fig. 4 of the drawings, while the longer end portion 21 of the rod is normally concentrically spaced from the surface of the main section of the bore 19. The extremity of this longer portion 21 of the fulcrum rod which extends

beyond one end of the tubular armature is rigidly fixed or clamped in the end of a post 26 which is suitably mounted on the front plate 16.

As also illustrated in Figure 4 of the drawing, the opposite ends of the tubular armature 18 project beyond the ends of the spool bore and are disposed between the complementary opposed shoes of the pole pieces 6 and 7 of the permanent magnet. The end portion 22 of the vibratory fulcrum rod or support 17 for the armature is formed with a longitudinally extending lug 27 projecting beyond the end of the armature and to said lug one end of the rod 28 is pivotally connected. This rod at its other end is adjustably connected as at 29 to the center of a diaphragm 30. This diaphragm may be constructed of any suitable material now generally employed for this purpose, though I preferably use a diaphragm principally constructed of celluloid and from which I have found a maximum amplitude of movement may be obtained in the vibratory movements of the magnet armature. However, I do not claim such a diaphragm in the present application, as it constitutes the subject matter of an independent invention which I have described and claimed in a co-pending application for patent filed March 23, 1923, Serial No. 627,063.

From reference to Figure 1 of the drawing, it will be understood that suitable binding posts are mounted on the front plate 16 and insulated from each other to which the ends of the magnet translating coil and the wires of the telephonic receiving circuit are respectively connected.

The magnetic structure above described is enclosed within a casing 31 of hard rubber or other suitable material which is exteriorly threaded at one end to receive the usual ear piece 32 having a central opening therein through which the sounds caused by vibration of the diaphragm 30 are disseminated.

In the operation of the telephone instrument above described, it will be understood that the alternating currents coming in over the line are translated by the electromagnetic coil and as long as the magnetic flux of the pole pieces is equal, the tubular armature and its fulcrum support will remain in a normal position in coinciding axial relation to the bore of the coil spool. The passage of fluctuating voice currents over the receiving circuit causes changes in direction and strength of the magnetic flux in accordance with the variations in the voice currents and thus produces a corresponding variation in the attraction and repulsion of the armature relative to the pole shoes. The relatively thin intermediate section 23 of the armature support possesses such inherent resiliency

that the end portion 22 of said support is caused to vibrate when the opposite ends of the tubular armature are acted upon by the variations in strength of the magnetic currents, as above explained. The center of such vibratory movements is at the fulcrum 25, which fulcrum, it will be observed, is located exactly midway between the ends of the tubular armature and precisely in line with its axis. Therefore, it is apparent that in the vibration of the end portion 22 of the support 17, the tubular armature moves therewith and the extent of movement of this end of the support and the corresponding end of the armature in one direction is exactly equaled by the extent of movement of the opposite end of the armature in the other direction. Thus, while the armature may freely vibrate in the bore of the coil spool, such vibration takes place from a point centrally located in the line of the armature axis so that the vibrating movement which is transmitted through the rod 28 to the diaphragm is caused solely by the fluctuating voice currents and there is no false movement produced owing to the location of the fulcrum point of the armature or other mechanical influences which to some extent, would modify the accurate reproduction of the voice currents in the form of sound tones. In other words, I have found that by thus mounting the armature so as to insure a correct vibratory movement thereof from a fulcrum located at the geometrical center of its structure so that the movements of the armature ends in opposite directions under the influence of the magnetic flux are exactly equalized, there is secured a very loud and remarkably clear reproduction of the voice currents in the form of sound. It will be appreciated that this new mounting for the armature is exceedingly simple, and that the production cost thereof and consequently, the selling price of the instrument in which the magnetic structure is embodied, will be materially less than that of similar instruments now in general use and which are of relatively complicated construction.

In Figure 6 of the drawing I have illustrated another possible form of the vibratory armature support in which the rod 17' has an intermediate reduced cylindrical section 23', the central part of which is of minimum diameter and constitutes the fulcrum point or center of vibration of the armature. It may also be possible in certain instances to employ an armature support 17^a, as shown in Figure 7, which is of uniform diameter throughout its length. It is of course, understood that the point of fulcrum of an armature of this form would be determined by its length and the distance from its fixed end exteriorly of the coil spool to the point at which the other end of the sup-

port is fixed in the armature, and that of course the strength of the magnetic currents and the inherent resiliency in the structure of the armature support would be accurately predetermined. However, for most practical purposes in the small powered radio receiving set, I have found the armature mounting as shown in Figures 4 and 5 of the drawing, admirably answers the desired purpose. 75

While primarily, the present invention is designed for use as a telephone receiver, it is obvious that the instrument might also be used as a transmitter, since when the sound waves of the voice are impressed upon the diaphragm, the vibration of the latter causes a movement of the armature. This produces electrical impulses in the coil which will be transmitted over the line. 80

I have herein shown and described a construction of my improved telephone apparatus which in actual operation has been found entirely practical. It is possible, however, that in certain commercial adaptations of my present improvements it may be found desirable or necessary to resort to certain mechanical changes in the form and construction of the armature or its vibratory support. Accordingly, it is to be understood that I do not desire to be limited to the precise details to which I have herein referred, but reserve the privilege of adopting all such legitimate changes in the form, construction and relative arrangements of the several parts as may be fairly embodied within the spirit and scope of the invention as claimed. 95

I claim:

1. An armature for magnet telephones, and resilient fulcrum means for said armature having the physical and geometrical fulcrum axis thereof intersecting the longitudinal axis of said armature. 105
2. In telephonic apparatus, a tubular magnet armature and a vibratory support coaxially positioned through said armature and having a fulcrum located within the bore of said tubular armature. 110
3. In telephonic apparatus, a tubular armature and a support extending longitudinally through the armature and having a vibratory part fixed to the armature and provided with a fulcrum located midway between the ends of the armature. 115
4. In telephonic apparatus, a tubular armature and a support extending longitudinally through the armature and having a vibratory part fixed to the armature and provided with a fulcrum located midway between the ends of the armature and in the line of its axis. 120
5. In telephonic apparatus, a magnet coil, an armature extending through the bore of said coil, and a vibratory support for the armature having a part of its structure 125

formed to provide a fulcrum centrally positioned between the ends of the armature and intersecting the axis thereof.

6. In telephonic apparatus, a magnet armature, a support for said armature fixed at one of its ends in spaced relation to the armature and having a vibratory part connected to the armature, said vibratory part having a fulcrum positioned midway between the ends of the armature and intersecting the axis thereof.

7. An armature for magnetic telephones and fulcrum means therefor, said means and the armature having coacting parts retaining the fulcrum means and armature in assembled relation for arrangement as a unit in operative relation to the telephone magnet, said means having a fulcrum centrally positioned between the ends of the armature and in line with the axis thereof, and supporting said armature for vibratory movement relative to the telephone magnet.

8. A tubular armature for magnet telephones, and a fulcrum member for the armature fixed in one end of the armature bore to normally support the armature in neutral position for vibratory movement between the magnet poles, said support extending through the armature and fixed at its other end independently of the armature and having a fulcrum located centrally between the ends of the armature and intersecting the axis thereof.

9. A tubular armature for magnet telephones, and a vibratory supporting rod fixed in one end of the bore of the armature and extending longitudinally therethrough, means for fixedly securing the rod at its other end, said rod having a reduced intermediate section providing a fulcrum located centrally between the ends of the armature bore and intersecting the axis thereof.

10. In telephonic apparatus, a tubular armature and a fulcrum member supporting said armature for oscillatory vibration and

having a part fixed within the bore of the armature for vibration with respect to a fulcrum located intermediate the ends of the armature.

11. In telephonic apparatus, a tubular armature and a support for said armature consisting of a rod having a vibratory end portion frictionally engaged with the wall of the armature bore and having its fulcrum intersecting the longitudinal axis of the armature.

12. In telephonic apparatus, a tubular armature, a supporting member fixed at one of its ends and having a vibratory portion normally coaxially related with said armature, and fixed within one end of the armature bore.

13. In telephonic apparatus, a tubular armature, supporting means therefor including a part secured in fixed relation to the armature exteriorly of the armature bore and a vibratory part extending within and closing one end of the bore of the armature and having a frictional connection with the wall thereof.

14. In telephonic apparatus, a tubular armature having one end of its bore of reduced diameter, a supporting member for said armature extending through the bore thereof having a part normally spaced concentrically from the wall of the armature, and another vibratory part of said member being fixed within the reduced end of the armature bore.

15. In telephonic apparatus, a tubular armature having one end of its bore of reduced diameter, a rod extending through said armature and having a vibratory end portion fixed in the reduced end of the armature bore, the wall of the armature for the remainder of its length being normally concentrically spaced from said rod.

In testimony that I claim the foregoing as my invention, I have signed my name hereunder:

LAMBERT SCHMIDT.
